UNITED STATES PATENT OFFICE.

VICTOR HUGO EMERSON, OF NEW YORK, N. Y., ASSIGNOR TO EMERSON PHONOGRAPH CO., INC., A CORPORATION OF NEW YORK.

METHOD OF PRODUCING SOUND-RECORDS.

1,299,153.

Specification of Letters Patent.

Patented Apr. 1, 1919.

Application filed July 24, 1915. Serial No. 41,635.

To all whom it may concern:

Be it known that I, VICTOR HUGO EMERSON, a citizen of the United States, residing in the city, county, and State of New York, 5 have invented certain new and useful Improvements in Methods of Producing Sound-Records, fully described and represented in the following specification and the accompanying drawings, forming a part of the 10 same.

My invention relates to sound records, and more particularly to those of the type having grooves with lateral undulations, and has for an object to provide a method for 15 reproducing with maximum accuracy and fidelity sound records of the class described.

In producing the commercial form of such records the usual practice is to cut into a blank of suitable record material, so called, a 20 groove or grooves having undulations corresponding to sound waves, and to make a male copy thereof having a raised portion with irregularities corresponding to those of the grooves, which copy is also called a 25 matrix, and is in turn employed in stamping or dieing out the commercial records.

My process more particularly relates to improvements in the first steps referred to, 30 namely, in preparing a built-up record blank having its groove formed in a prescribed manner, and employing in connection therewith the usual electrolytic process with the desired result of entirely filling out the 35 grooves of the sound record blank with the electrolytic deposit, by means of eliminating from the walls thereof the inner lining of conductive material that has heretofore been used in making electro-matrices.

In the familiar process of electrolysis, the 40 electroplate deposit requires an electric conducting medium, and accordingly I form my record blank with a suitable electro-conductive plate of the form of the record required, preferably made of a sheet of hard metal, such as hard brass, upon which as a base, I 45 lay to the required depth a coating of suitable record material.

I then form the usual sound record groove 50 with any of the familiar types of recording devices adapted to vibrate laterally, preferably using a stylus having a V-shaped recording point, slightly blunted and resting upon the underlying electroconductive base which when formed of sufficiently hard 55 metal will resist the cutting tendency of the

stylus while the record material is being removed thereby. Thus a groove of even depth will be formed in the top surface of the record blank having lateral undulations corresponding to the sound waves recorded. 60 The flat or tablet form of disk is preferably employed in the practice of my improved method of production, to which the rotary motion is imparted in the usual way to form a spiral of the sound record groove, the 65 edges of the successive laps thereof being practically contiguous, that is, the width of the wall separating the grooves being reduced to a minimum, allowing only for the irregularities of the undulations thereof. In 70 thus forming a sound record groove in a blank formed in the manner described, the recording stylus in cutting the groove removes the material of the superimposed layer, thereby exposing for electric contact 75 the electro-conductive base, and the record thus prepared is now ready for introduction into the electrolytic bath; and in this connection it will be observed that a groove thus formed for electroplating will be wholly 80 free from foreign substances, thereby producing an absolutely accurate duplicate of the original.

For reasons hereinafter explained more 85 in detail, the groove may be prolonged at both ends, as illustrated in my preferred method, so as to cover substantially the face 90 of the disk which extended portions will have all the characteristics of the sound record groove excepting the undulatory feature thereof.

The foregoing then constitutes the essential 95 features of the initial steps of my process, and generically described, the remaining stages relative to the consummation thereof consist in completing the electroplate formed as described, which in the usual way is prepared as a die or male matrix for stamping or imprinting the record thereon into blanks for producing commercial records. 100

I represent in the drawings hereto attached a portion of the apparatus and products employed incidentally in the practice of my improved process, of which 105 Figure 1 is illustrative of a sound record tablet of the flat rotatable type with a spiral groove covering the face thereof, a portion having lateral undulations; Fig. 2 is an enlarged diametral sectional view of 110

a portion of a record tablet similar to that shown in Fig. 1, with the recording point of a stylus in position to form the groove therein; this view shows a record ready for the electroplating process on completion of groove spiral. Fig. 3 is also a partial cross-sectional view giving details of groove construction upon an enlarged scale as in Fig. 2, showing in part the matrix formed in the electrolytic bath.

Having reference to the drawings: The numeral 1 represents a sound record of the rotatable disk type composed of an underlying base plate 2 preferably made of hard brass, having upon one surface thereof a coating of record material 3 which may be made of any of the well known compositions employed for receiving and preserving impressions made by the recording stylus, such as beeswax, paraffin, etc. The disk 1 thus prepared is rotated at a predetermined speed while a stylus 5 having its point 5^a cutting entirely through the coating and resting upon the underlying plate 2, engraves by a suitably controlled mechanism a spiral form of groove 4 in the face of record 1, through a portion of which the stylus is caused to vibrate in producing in the usual manner lateral undulations 4^a in the form shown in Fig. 2. The grooves thus formed by the stylus as they lap are separated by a wall of slight thickness, and in the practice of my invention I find it preferable to provide the wall between the grooves with a minimum of width consistent with the maximum amplitude of the undulations of contiguous portions of the spiral groove.

The slightly blunted point of the stylus thus drawn along and scraping the record material from the face of the metal base plate of the blank exposes the surface thereof in the process just described as a finely traced line, forming the bottom of the groove 4. Upon this narrow exposure of the underlying metal surface the electroplate 6 will begin to form by the deposit thereon of the atoms of the metal which characterizes the electrolyte employed, technically known as ions, or kathions, as they would be more specifically described when metallic salts as at present preferably employed constitute the basis of the solution.

In practising my invention I preferably use a copper solution, and the minute particles of this metal thus deposited upon a slender zig-zag base as a beginning, as the electrolytic process continues are added one upon another in constantly widening layers until the top of the groove is reached; as this process advances the deposited metal rises along the walls of contiguous grooves and unites at the respective top edges thereof to form a continuous sheet of copper

electroplate. Thus all portions of the spiral groove 4 are completely filled out thereby producing the raised spiral 7 which, it will be readily understood, is in form and in all its details the exact male counterpart 70 of the grooved spiral 4 and which during the progress of the formation has been merely guided by and physically molded within the walls 4^b of the grooves 4 and not electrolytically deposited upon a conducting medium overlaid upon and lining said wall surfaces 4^b as heretofore employed. 75

The groove 4 it will be apparent as made in the form illustrated and covering the entire surface of the record conveniently 80 serves the purpose of extending the electroplate over the full area of the record. On the other hand, should such an original record be prepared for the electrolytic process as described herein, except that a part 85 only of the groove be present, namely, the sound record portion 4 as now usually employed, in that case the electro-plate deposited thereon would be limited to the part having the groove spiral, for the reason 90 that the electric current is conducted toward that portion of the record blank.

Such an electroplate however would take the form of an annular disk, that is, one having the sound record complete but without 95 a central portion or outer rim, and which would therefore preferably require reinforcement of one kind or another to fit it for the use for which it is intended. This annular portion could be sweated upon a 100 plate of suitable form, or such inner and outer portions could be supplied by the electrolytic process in the usual way. But in either of the proposed methods there would result an unevenness in the superficial plane 105 of the matrix record thus formed which would entail further care and attention in obviating such irregularity. This end I attain in a most convenient and satisfactory method as described, namely by continuing 110 the groove 4 all the way from the circumference to the center. The electroplate is thereupon made of uniform thickness throughout and the electrodeposit may be continued until any desired strength of material is obtained. 115

The matrix thus deposited in the form of a thin copper sheet may be readily separated from the grooved original or master record, the union between the raised portions 120 or ridges 7 and the base plate 2 of the disk 1 being easily broken owing to the comparatively small area of contact of the narrowed top portions of the raised spiral and the metal plate to which it adheres. 125

The matrix thus produced may thereupon be employed in the usual manner of manufacturing copies of the original record that had been prepared in accordance with the process hereinabove described, free from in- 130

accuracies unavoidably due to extraneous or obtrusive foreign deposits in the grooves recorded therein, with the highly beneficial result that an improved record may be 5 formed which will with practically undiminished fidelity and precision reproduce the sounds originally recorded for the purpose of manifold reproduction.

Having described my invention, what I 10 claim is:

1. In producing sound records, the herein described method of making male matrices which consists of, first, preparing a blank having an electro-conductive base and a 15 layer of record material thereon, then making an original sound record by cutting a groove of uniform depth in said record material by means of a laterally vibratile recording stylus and exposing for electrolytic 20 action the surface of said base at the bottom of the groove thus formed; then forming a matrix thereon by electrolysis; and finally separating said matrix from said base material.

25 2. The process of producing sound records which consists of first preparing a record blank having a base portion of electro-conductive material and a layer of suitable record material superimposed thereon; then 30 forming an original sound record on said blank by cutting an undulatory groove in said superimposed layer and exposing the surface of said base at the bottom of said groove, said exposed surface having undulations corresponding to and representative of 35 sound vibrations; then forming a male matrix thereon by electrolysis, and thereupon employing said matrix for reproducing copies of the original sound record.

40 3. The process of producing sound records which consists of first preparing a record blank having a plurality of layers, one of said layers constituting a base of electro-conductive material with another layer superimposed thereon comprising a wax-like 45 record material, then forming an original sound record by cutting a groove in said

superimposed layer having undulations corresponding to and representative of sound vibrations, and exposing the surface of said base at the bottom of said groove; then forming a male matrix thereon by electrolysis; and thereupon employing said matrix for reproducing copies of the original said record.

55

4. In producing sound records the herein described method of making male matrices which consists of, first, preparing a blank having an electro-conductive base and a layer of suitable record material thereon; then cutting a spiral groove of uniform depth in said record material by means of a laterally vibratile recording stylus caused to vibrate in recording sound waves within a portion only of said groove and exposing thereby for electrolytic action the surface of said base at the bottom of the groove thus formed; then forming a male matrix thereon by electrolysis; and finally separating said matrix from said base.

65

5. In producing sound record disk tablets, the herein described method of making male matrices which consists of, first, preparing a circular blank having an electro-conductive base and a layer of suitable record material thereon; then cutting by means of a suitable stylus a spiral groove of uniform depth in said record material, said spiral extending substantially over the entire surface of said blank and exposing for electrolytic action the surface of said base at the bottom of the groove thus formed, causing said stylus to vibrate laterally within a portion only of said groove to record sound waves therein; then forming a matrix thereon by electrolysis; and finally separating said matrix from said base.

75

In testimony whereof, I have hereunto set my hand in the presence of two subscribing witnesses,

VICTOR HUGO EMERSON.
